UNITED STATES PATENT OFFICE

150,697

DESIGN FOR A PIN-UP HAT TREE

Beatrice Judd, Richmond, Va.

Application January 24, 1947, Serial No. 136,357

Term of patent 7 years

(Cl. D17—12)

To all whom it may concern:

Be it known that I, Beatrice Judd, a citizen of the United States, residing in the city of Richmond, State of Virginia, have invented a new, original, and ornamental Design for a Pin-Up Hat Tree, of which the following is a specification, reference being had to the accompanying drawing, forming part thereof.

Fig. 1 is a perspective view of a pin-up hat tree, showing my new design.

Fig. 2 is a front elevational view of the same.
Fig. 3 is a side elevational view thereof.

I claim:

The ornamental design for a pin-up hat tree, as shown.

BEATRICE JUDD.
